CLAIM

The ornamental design for a plastic bag support with integral hinged cover, substantially as shown and described.

DESCRIPTION

FIG. 1 is a top plan view of a plastic bag support with integral hinged cover showing my new design;

FIG. 2 is a view looking in the direction of the arrows 2—2 of FIG. 1;

FIG. 3 is an enlarged sectional view taken on line 3—3 of FIG. 1 with a portion of a bag being shown in broken lines for illustrative purposes only;

FIG. 4 is a bottom plan view; and

FIG. 5 is a view looking in the direction of the arrows 5—5 of FIG. 1 with the cover in a partially opened condition.
